B. Fitts,
Wood Planing Machine.
N° 17,963. Patented Aug. 11, 1857.

UNITED STATES PATENT OFFICE.

BENAIAH FITTS, OF WORCESTER, MASSACHUSETTS.

ARRANGEMENT OF FEED-ROLLERS FOR PLANING-MACHINES.

Specification of Letters Patent No. 17,963, dated August 11, 1857.

To all whom it may concern:

Be it known that I, BENAIAH FITTS, of the city and county of Worcester and State of Massachusetts, have invented a new and useful Improvement in Driving Gears on Feed-Rolls for Wood-Planing Machines; and I do hereby declare that the following is a full, clear, and exact description of the construction and operation of the same, reference being had to the annexed drawings, which compose a part of this specification, and which is a perspective view.

The machine consists of a frame A, on which the other parts rest.

15 B and C are feed rolls for feeding the lumber into the machine, having shafts or bearings projecting far enough at one end to receive the gears,—D, the cutting cylinder,—E, E, a frame in which hangs the cylinder D, and top feed roll B, and may be raised or lowered for different thicknesses of lumber,—F, an internal and external gear made fast on roll shaft C,—G, an external gear made fast on roll shaft B. The size 20 of the rolls to correspond with that of the gears so that the surfaces of B, and C, shall move with the same velocity. H, a pinion meshing into internal gear F, and external gear G.

25 I, and J, are connecting arms holding firmly at one end the shaft on which the pinion H, revolves, the other ends being attached—I, to the roll shaft B, and J, to the roll shaft C, thus allowing the roll B, to move up or down, the pinion being held firmly in gear, communicating the desired motion from F, to G.

30 L, is the shaft to which the power is applied to drive the rolls—M, screws on which

are gears for raising the frame E,—N, the 40 crank shaft on which are gears for raising the frame E,—O, pulley for driving cutting cylinder—P, a gage to guide the board through the machine—R, a roll, joint and spring to hold the board against the gage P. 45

I am aware that internal and external gear have been used for similar purposes, the gears being attached at the opposite ends of the roll shafts, motion being communicated from one to the other by pinions 50 on the end of a shaft which vibrates at one end as the roll is raised or lowered.

The characteristic features of my invention are, the arranging the size of the rolls to correspond with that of the gears so that 55 their surfaces shall move with equal velocity; and also the holding of the stud or shaft on which the pinion H, revolves by the connecting arms I, and J, as described, so that the pinion is held firmly in gear 60 when the roll B, is raised or lowered in combination with the internal and external gears.

What I claim and desire to secure by Letters Patent in driving gears or feed rolls for 65 wood planing machines, is—

The internal gear F, and the external gear G, in combination with the pinion H, and connecting arms I, and J, when constructed and operated as set forth and de- 70 scribed.

In testimony whereof I have hereunto set my hand and seal, in the presence of two witnesses.

BENAIAH FITTS. [L.s.]

Witnesses:

E. C. TAINTER,
E. A. WOOD.
